(57) **CLAIM**

The ornamental design of a contoured scrubber, as shown and described.

DESCRIPTION

FIG. 1 is a top perspective view of the first embodiment.

FIG. 2 is a front view of the first embodiment.

FIG. 3 is back view of the first embodiment.

FIG. 4 is a first side view of the first embodiment.

FIG. 5 is a second side view of the first embodiment.

FIG. 6 is a top view of the first embodiment.

FIG. 7 is a bottom view of the first embodiment.

FIG. 8 is a top perspective view of an alternate embodiment.

FIG. 9 is top perspective view of a second alternate embodiment; and,

FIG. 10 is a top perspective view of a third alternate embodiment.
